ADJUSTABLE CHAISE LOUNGE

Morton Pearlstine, Cynwyd, Pa., assignor to The Bunting Company, Inc., Philadelphia, Pa., a corporation of Pennsylvania

Application June 21, 1955, Serial No. 36,619

Term of patent 14 years

(Cl. D15—11)

I claim:

The ornamental design for an adjustable chaise lounge, as shown.
